UNITED STATES PATENT OFFICE

JOSEPH D. SWARNER, OF KANSAS CITY, KANSAS

CLOSURE OPERATOR

Application filed August 2, 1929. Serial No. 382,886.

This invention relates to new and useful improvements in closure operators, and more particularly to a novel mechanism for automatically operating garage doors.

5 A principal object of the invention is to provide an automatic mechanism operated by the vehicle for both opening and closing the garage doors.

Another object of the invention is to provide 10 a closure operating mechanism of the character mentioned which because of its simple construction can be manufactured and installed at low cost.

15 These and numerous other important objects and advantages of the invention will become more apparent to the reader after considering the invention as described and claimed hereinafter.

In the drawings:

20 Figure 1 represents a fragmentary side elevation of a garage partly broken away and disclosing the novel mechanism associated with the door thereof.

25 Figure 2 represents a fragmentary horizontal sectional view through a garage and showing the novel door operating mechanism mounted in conjunction therewith.

30 Figure 3 represents a fragmentary horizontal sectional view through a garage showing the mechanism operated and with the doors in open position.

Referring to the drawings wherein like numerals designate like parts, it will be seen that 35 5 represents a garage of conventional construction having a roof 7 and twin doors 8—8 hingedly mounted in the usual manner.

A bracket 9 supports a rocker arm 10, one end of which has a link connection 11 with a member 12 on one of the doors 8. A pair of 40 U-shaped plates 13 and 14 cooperate with the link 15 and bracket 16 to afford an adjustable connection. The U-shaped member 14 is shorter than the member 13 and set screws 17—17 engaged through the end portions of the member 13 to bear against the end portions of the member 14 whereby the pin and slot connection 18 may be adjusted to meet requirements. A bracket 19 is provided on the complementary doors 8 and a pivotal link 20 connects the bracket 19 with the arm 15.

A crank shaft 21 is mounted on the bearings 22—22 over the driveway 23 leading to the garage. The crank shaft 21 is provided with the offset cranks 24 and 25. A connecting rod 26 connects one end of the crank shaft 21 to the outer end of the rocker arm 10 as in the manner clearly shown in Figure 3.

A bracket 27 is secured to the inner side of one of the doors 8 and a connecting rod 28 leads therefrom and connects to the crank 29 and the crank 30. An L-shaped frame arrangement 31 is provided on the shaft 29 and this shaft 29 is journaled through the bearings 32—32.

It will thus be seen that when a vehicle 65 approaching the garage engages the upstanding crank 25, the mechanism will be set in motion to open the doors 8—8 to the position shown in Figure 3. In this position of the doors, the cranks will be in the positions shown and when the vehicle engages the L-shaped frame 31 at the inside of the garage, the doors 8—8 will be shifted to a closed position. Obviously as the vehicle 70 moves away from the garage on the driveway 75 23, the engagement of one of the wheels against the upstanding crank 24 (while the doors 8—8 are in open position) will result in the closing of the doors.

While the foregoing description has been 80 in specific terms, it is to be understood that numerous changes in the shape, size and materials may be resorted to without departing from the spirit and scope of the invention as claimed hereinafter.

Having thus described the invention, what is claimed as new is:

1. An operating mechanism for swinging doors comprising a rocker arm, a linked connection between one end of the rocker arm and the door, a crank shaft at each side of the door, a connecting rod between the opposite end of the rocker arm and one of the crank shafts, and a connecting rod pivoted at one end to the said door and having its opposite end connected to the other crank shaft.

2. An operating mechanism for swinging doors comprising a rocker arm, a linked connection between one end of the rocker arm and the door, a crank shaft at each side of the

door, a connecting rod between the opposite end of the rocker arm and one of the crank shafts, and a connecting rod pivoted at one end to the said door and having its opposite end connected to the other crank shaft, the first mentioned crank shaft being provided with a pair of opposite cranks thereon, while the other crank shaft is provided with an L-shaped frame thereon.

20 In testimony whereof I affix my signature.
JOSEPH D. SWARNER.
